DOFFING MEANS FOR COTTON PICKERS

Filed April 10, 1935

UNITED STATES PATENT OFFICE

2,034,907

DOFFING MEANS FOR COTTON PICKERS

Edward A. Johnston, Chicago, Ill., assignor to International Harvester Company, a corporation of New Jersey

Application April 10, 1935, Serial No. 15,536

13 Claims. (Cl. 56—40)

This invention relates to cotton pickers. More specifically, it relates to an improvement in the doffing means for a cotton picker of the rotating spindle type.

5 The principal object of the present invention is to provide an improved doffing mechanism which is more effective in removing cotton from a rotating picking spindle than the doffing means heretofore employed.

10 Another object is to provide doffing means incorporating a positive, rigid doffing element and a resilient doffing element, whereby the advantages of each type may be obtained.

These objects and others, which will be apparent from the detailed description to follow, are attained by a construction as shown in the drawing, in which:

15 Figure 1 is a plan view, showing a portion of a rotating spindle type of doffer drum and a doffing means therefor embodying the invention;

20 Figure 2 is a vertical section through the axis of the doffing means, showing the picking drum in elevation;

25 Figure 3 is a section through the axis of a modified form of doffing means;

Figure 4 is a top plan view of the positive doffing member; and,

30 Figure 5 is a top plan view of the doffing member carrying the resilient doffing means.

35 Cotton pickers embodying a revolving drum on which rotating picker spindles are carried are well known in the art. In the later developments, the spindles have been constructed to assist in the doffing of the cotton fibers therefrom.

40 The Edward A. Johnston Patent No. 1,883,506 shows a cotton picker of the rotating spindle type, in which the spindles are conical and are arranged at an angle to provide a doffing area of contact to facilitate the removal of fibers. It

45 is on a picker of this particular type that the present invention is adapted to be embodied. As said patent shows the drum driving and supporting means, and, as such structures are well known in the prior art, only such elements have been shown in the drawing of this application as are necessary to describe the function of the improved doffing means, which is the subject-matter of this invention.

50 The rotating picking drum 10, carrying mounted thereon a plurality of rotatable conical picking spindles 11, has been shown only diagrammatically, being the same in construction and operation as shown in the patent above referred to. The drum 10 is driven at a uniform speed

5 which carries the spindles 11 at a speed substantially the same as the speed of travel of the frame structure on which the drum is mounted. The cotton plants are directed into contact with the picking spindles as well known in the art and as shown in the patent above referred to. The drum continues to rotate after contact with the plant and comes into contact with the doffing means. By arranging the conical spindles at an angle, as illustrated, the upper edges of the spindles lie 10 in planes perpendicular to the axis of the drum, whereby said edges, in the rotation of the drum and of the spindles, form a plain surface for doffing, which makes possible a doffing action over an area of contact, instead of a line contact, of 15 such a construction as herein provided.

20 In the doffing of spindles of the type illustrated, it has been found desirable to utilize positive doffing elements operating as close to the spindles as possible without actual contact therewith. Such positive doffing elements remove any cotton bolls or other foreign material which may be carried by the spindles, as well as the major portion of the cotton fibers. However, it is also important to provide a resilient doffing element in 25 actual contact with the spindles to remove the remaining fibers and to maintain the spindles in a clean condition. If there is no actual contacting doffing means, a deposit of gum is apt to form on the spindles, with which the cotton 30 fibers engage, forming a substance which cannot be removed by doffing means in any manner. These points, important in the doffing of cotton from picking spindles, have been mentioned to give a background for the present invention and 35 to illustrate its utility and its advance in the art.

40 The main frame 12, a portion of which is shown in Figure 2, on which the cotton picker is carried, forms a support for a ball bearing assembly 13, in which the lower end of the doffing unit is mounted for rotation on a vertical axis. The upper bearing has not been shown, the member 14 which carries sprocket teeth being broken away at the upper end. Means are provided for rotating the doffer unit at the proper 45 angular velocity. As illustrated, the doffer unit consists of a shaft 15, on which a plurality of doffing members 16 are mounted. Said members include sleeves 17, which abut each other, being positively clamped in position on the shaft 15 50 by a nut 17'. As shown in Figure 4, the doffing member 16 includes a plurality of doffing portions in the form of blades 18, which project radially and are formed with horizontal edges aligned in a plane perpendicular to the axis of 55

the shaft 15. The edges of said doffing blades are positioned and adjusted to operate closely adjacent the upper surfaces of the respective rows of picking spindles 11. The blades are set 5 to operate as closely as possible to the picking spindles without actual contact therewith during operation of the machine. Said blades accomplish the major amount of doffing, leaving only closely wrapped cotton fibers and other material which may closely adhere to the picking spindles. Secondary doffing members 19 are slidably mounted on the sleeve portions 17 of the primary doffing members 16. The secondary members are provided with portions 20 extending 10 outwardly between the blades 18 and carrying two rows of spirally arranged bristles 21. Said bristles contact the upper surfaces of the spindles during operation of the machine. It will be noted that the secondary doffing members 19 are free to slide vertically with respect to the doffing members 16. The weight of said secondary members maintains the bristles 21 in contact with the picking spindles. Wear of the bristles is automatically taken care of by pressure down- 15 wardly individually of the doffing members 19. In some conditions it may be desirable to utilize additional pressure upon the doffing members, as illustrated by the spring 22 shown in the modification of Figure 3. It will be noted that the 20 lower portions of the doffing members 19 engage the upper portions of the next adjacent lower doffing member 16 after the bristles have worn a substantial amount. This stop is provided to prevent actual engagement of the metallic parts 25 of the doffing members 19 with the spindles.

The spiral arrangement of the bristles assists in the doffing action, as will be understood by an inspection of Figure 1, which shows by arrows the direction of rotation of the picking drum 40 and of the doffing unit. It will be noted that the doffing blades 18 first describe the doffing area, passing endwise from the outer ends of the spindles toward their bases. The positive blades, therefore, carry the major portion of the doffing 45 action and the load and wear, which might otherwise be transmitted to the doffing bristles 21. Said bristles follow the path of the doffing blades, being arranged spirally to obtain more of an axial stroke along the spindles, which facilitates 50 removal of the cotton fibers wrapped circumferentially around the spindles. By this construction an effective and long life doffing means has been provided, the major doffing action being accomplished by positive, rigid elements, 55 which can be constructed of metal to practically eliminate wear. The bristles, which follow contact with the spindles by a slight pressure, effectively remove the remainder of the material from the spindles without undue wear on the 60 bristles.

It will be understood that applicant has shown and described only a preferred embodiment of his improved dual type of doffing means and that he claims as his invention all modifications there- 65 of falling within the scope of the appended claims.

What is claimed is:

1. In a cotton picker having a rotating drum carrying a plurality of rotating picking spindles, 70 and in combination therewith; a rotatable doffer shaft, a plurality of doffer members fixed on said shaft in spaced relation, each of said doffer members includind portions positioned to pass in close proximity to some of the spindles, and a plurality 75 of doffing members slidably mounted on the

doffer shaft below the first named doffing members, said members carrying doffing bristles positioned to engage the surface of the picking spindles.

2. In a cotton picker having a rotating drum 5 carrying a plurality of rotating picking spindles, and in combination therewith; a rotatable doffer shaft, a plurality of doffer members fixed on said shaft in spaced relation, each of said doffer members including a plurality of circumferentially 10 spaced doffing elements positioned to pass in close proximity to the edges of a row of spindles, and a plurality of doffing members slidably mounted on the doffer shaft, said members carrying doffing bristles positioned to engage the surface of 15 the picking spindles between the doffing elements.

3. In a cotton picker having a rotating drum carrying a plurality of rotating picking spindles arranged in a circumferential row, and in combination therewith; a doffer member rotatable 20 about a fixed axis in a fixed plane and including doffing portions positioned to pass in close proximity to the edges of a row of spindles, and a second rotatable doffer member having doffing elements 25 slidably mounted between the doffing portions first named doffing member, said doffing elements being positioned to engage the surface of the picking spindles.

4. In a cotton picker having a rotating drum carrying a plurality of tapered picking spindles 30 arranged in circumferential, axially spaced rows with the spindles positioned at an angle whereby corresponding edges of the spindles in each row lie in a plane perpendicular to the axis of the drum, and in combination therewith; a rotatable 35 doffer shaft arranged parallel to the axis of the drum, a plurality of doffer members fixed on said shaft in spaced relation, each of said doffer members including a plurality of circumferentially 40 spaced doffing elements positioned to pass in close proximity to the edges of a row of spindles, and a plurality of doffing members slidably mounted on the doffer shaft, said members carrying doffing means positioned to engage the surface of the 45 picking spindles between the doffing elements of the first named doffing members.

5. A device as set forth in claim 4, in which resilient means are provided for maintaining the doffing bristles in contact with the picking spindles. 50

6. In a cotton picker having a rotating drum carrying a plurality of tapered picking spindles arranged in circumferential, axially spaced rows with the spindles positioned at an angle whereby corresponding edges of the spindles in each row 55 lie in a plane perpendicular to the axis of the drum, and in combination therewith; a rotatable doffer shaft arranged parallel to the axis of the drum, a plurality of doffer members fixed on said shaft in spaced relation, each of said doffer members including a plurality of circumferentially 60 spaced doffing elements positioned to pass in close proximity to the edges of a row of spindles, and a plurality of doffing members slidably mounted on the doffer shaft, said members carrying sets of 65 doffing bristles arranged in spiral formation with each set positioned to engage the surface of the picking spindles between adjacent doffing elements.

7. A device as set forth in claim 6, in which resilient means are provided for maintaining the doffing bristles in contact with the picking spindles. 70

8. In a cotton picker and in combination, a frame structure, a drum rotatably mounted there- 75

- on, a row of rotatable picking spindles carried by said drum and arranged in a plane perpendicular to the axis of the drum, said spindles being conical and being positioned at an angle whereby corresponding edges of the picking surface lie in a plane perpendicular to the axis of the drum, a doffing member rotatably mounted on the frame structure, said member having rigid doffing portions positioned to pass over the edges of the spindles which lie in the plane in close proximity to said edges, and a second doffing member mounted for rotation with the first doffing member and being slidable along its axis of rotation with respect to said first doffing member, said second doffing member having doffing portions mounted circumferentially between the rigid doffing portions of the first doffing member and engaging said spindles.
9. A device as set forth in claim 8, in which the axis of the doffing members is vertically positioned and in which the second doffing member is below the first doffing member whereby contact with the doffing spindles is maintained by the weight of the second doffing member.
10. A device as set forth in claim 8, in which spring means are positioned between the two doffing members for maintaining the second doffing member in contact with the picking spindles.
11. A device as set forth in claim 8, in which the contact means between the second doffing member and the picking spindles is formed by resilient bristles and in which stop means are provided to limit movement of the second doffing member toward the spindles when the effective doffing portions of the bristles have been worn away.
12. A cotton picker comprising a drum struc-
- ture mounted for rotation, a series of conical picking fingers mounted for rotation on said drum, said fingers being positioned in axially spaced circumferential rows, said fingers extending outwardly from the drum and upwardly at such an angle that the upper edges of the fingers in each circumferential row lie in substantially the same plane, means for rotating the drum, means for rotating the fingers mounted thereon, and a doffing mechanism comprising a pair of rotatable doffing members mounted above each circumferential row of picking spindles, one of said members being fixed against movement axially of the picking drum and the other member being slidably mounted with respect to the first mentioned member and resiliently engaged with the picking spindles.
13. A cotton picker comprising a drum structure mounted for rotation, a series of conical picking fingers mounted for rotation on said drum, said fingers being positioned in axially spaced circumferential rows, said fingers extending outwardly from the drum and upwardly at such an angle that the upper edges of the fingers in each circumferential row lie in substantially the same plane, means for rotating the drum, means for rotating the fingers mounted thereon, and a doffing mechanism comprising a pair of rotatable doffing members mounted above each circumferential row of picking spindles, one of said members being fixed against movement axially of the picking drum and being provided with doffing blades positioned to operate closely adjacent the spindles, and the other member being slidably mounted with respect to the first mentioned member and resiliently engaged with the picking spindles.

EDWARD A. JOHNSTON.
